UNITED STATES PATENT OFFICE.

WILLIAM H. HULSE, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed June 12, 1920. Serial No. 388,401.

To all whom it may concern:

Be it known that I, WILLIAM H. HULSE, a citizen of the United States, residing in Brooklyn Borough, in the county of Kings, city and State of New York, have invented certain new and useful Improvements in Typewriting Machines, of which the following is a specification.

This invention relates to silent-key devices 10 of typewriting machines, whereby certain keys may be operated to print a plurality of characters, one above or below the other, without travel of the carriage.

The invention is illustrated as applied to 15 a typewriting machine of the form disclosed in the patent to Petermann, No. 1,189,171, dated June 27, 1916.

According to the present invention, the 20 silent-key or keys may be adapted to partially operate the usual universal bar, which actuates the escapement and the ribbon-vibrating mechanism. The connections may be such that the universal bar is temporarily latched in position to hold the ribbon covering 25 the printing point. At the return of the silent-key, the universal bar may remain locked; its release being automatically effected by the actuation of one of the usual letter-feeding keys.

30 There is provided upon the universal bar a hook, which is normally ineffective at the actuation of any letter-feeding key-lever, but which, at the actuation of a silent-key, swings and catches upon a fixed lug or pin, thus holding the universal bar in its actuated 35 position and holding the ribbon up to cover the printing point.

The hook may be controlled by an auxiliary cross-bar lying adjacent the main cross-bar 40 of the usual universal bar, the auxiliary cross-bar being adapted to be swung with the usual cross-bar by the usual lug provided on the key-levers.

The silent-key-lever or levers may be provided 45 with a shorter lug, which swings clear of the auxiliary cross-bar, thus permitting said cross-bar to swing relatively to the main part of the universal bar, and thereby swing to effective position the hook which locks the 50 universal bar. This locking of the universal

bar enables the silent-key, already actuated, or any other silent-key, which may be provided in the machine, to be actuated before the carriage letter-feeds, with the result that one or more silent-key characters may be 55 typed at the same letter-space prior to the typing of a character and the feeding of the carriage by a letter-feeding key.

Other features and advantages will hereinafter appear. 60

In the accompanying drawings,

Figure 1 is a sectional side view, largely diagrammatic, of a typewriting machine, showing the present invention as applied thereto. 65

Figure 2 is a similar view, showing a silent-key actuated to lock the universal bar and to print.

Figure 3 is a perspective view of the parts seen in Figure 2, but showing the parts in 70 normal position, as in Figure 1.

Figure 4 is a view similar to Figure 2, but showing a letter-feeding key actuated to release the universal bar and to type a character. 75

Type-keys 1, when depressed, swing key-levers 2 around their respective shafts on cross-bars 3, on which they are journaled by stirrups 4, so that the rear end 5 of each key-lever 2 rises when its key 1 is depressed, and 80 swings its type-bar 6 against the platen, because it is connected thereto by an upstanding link 7 pivoted to the type-bar 6 and to a lug 8 upstanding from the rear end of the key-lever. 85

As any type-bar 6 approaches the platen 9, its key-lever 2 lifts a cross-bar 10, forming a solid part of a universal bar which includes sides 11, and is journaled on a fixed bar 12. To enable the key-levers 2 to actuate the universal bar, each key-lever is provided with a lug 13, which projects horizontally from a downwardly curved portion 14 of the key-lever, with the result that the rising rear end 5 of the key-lever lifts the lug 13, and 90 causes the universal bar frame 10, 11 to draw upon links 15 pivotally attached to the sides 11 and adapted to draw forwardly the lower end 16 of an actuator lever 17 to which the links 15 are pivoted. 95

The rising of the universal bar is normally effective to feed the carriage one letter-space to the left, and, for this purpose, the carriage 18 is normally under tension of a spring barrel 19, which tends to draw it to the left. The carriage, however, is normally detained, because a loose dog 20 upon a dog rocker 21 is in mesh with a rack 22 connected to the typewriter carriage 18.

- 10 Whenever the universal bar rises in the manner described and rocks the actuator lever 17, a cross-bar 23 on the upper end of said lever rocks rearwardly a fork 24, extending downwardly from a rocking bar 25 extending across the machine and provided with a lug 26, which is adapted to push rearwardly the dog rocker 21, thus carrying the loose dog 20 clear of the rack 22 and carrying a fixed dog 27 into mesh with said rack.
- 15 The movement of the typewriter carriage at this time is negligible, because the fixed dog is adjusted to hold the carriage practically at the point where it was held by the loose dog. At the rise of the type-key 1, the universal bar frame 11 is drawn downwardly by a spring 28, thereby rocking the upper end of the lever 17 forwardly, with the result that the dog rocker 21 is swung forwardly by its spring 29, carrying the loose dog 20 into mesh with the rack 22. This feeds the carriage along one letter-space, because, at the release of the rack 22 from the loose dog 20, a spring 30 swings the loose dog into position to mesh with the next adjoining tooth of the rack 22.

The actuation of the universal bar not only thus actuates the mechanism including the dog rocker 21, but also actuates the ribbon carrier 31 to lift the ribbon 32 from its normal position below the printing point up to cover the printing point, so that the actuated type will print through the ribbon. For this purpose, the vibrating bar 25 is provided with a cam bracket 33, which is adapted to engage a roll 34 on the lower end of the short arm 35 of a bell-crank lever having a long arm 36, the end of which forms the ribbon carrier 31.

50 The form of the cam is such that pushing the vibrating bar 25 rearwardly lifts the ribbon carrier 31 to the printing point against the tension of its spring 37. The end of the arm 35 may be steadied in a guide bracket 38.

55 At the release of the type-key 1, the ribbon carrier swings downwardly partly under the tension of its spring 37 and partly under the tension of the returning spring 28. As thus far described, the parts may be to a large extent identical with those usually found in such machines.

60 According to the present invention, in addition to the letter-feeding type-keys 1, there may be also provided silent-keys 39, having key-levers 40, much like the key-levers 2, and connected by lugs 8 and links 7 to actuate

their respective type-bars. Each silent-key 39 may be provided with a lug 41 adapted to engage the universal bar by striking the cross-bar 10, thus drawing upon the link 15 and swinging the dog rocker 21 rearwardly 70 precisely as does any lug 13 when its letter-feeding type-bar is actuated.

The lugs 41 are cut off short because the universal bar is provided with a front auxiliary cross-bar 42 which usually rises at the rise of the cross-bar 10, because the lugs 13 underlie both the cross-bar 42 and the cross-bar 10. At the rise of the silent-key 39, however, its short lug 41 fails to actuate the auxiliary cross-bar 42, with the result that gravity holds it behind, while the cross-bar 10 rises, thus permitting a hook 43, extending upwardly from the pivot 44 upon the side 11 and upon which the cross-bar 42 is pivoted, to swing over and catch upon a fixed lug or pin 45 in front of it, thereby locking the universal bar 10, 11 in its actuated position. The construction is such that when the silent-key 39 rises, its lug 41 sinks down, leaving the universal bar held by the hook. This holds the ribbon carrier 31 in its raised position to which it was brought at the rising of the universal bar 10, 11, thus enabling the ribbon to be used for typing another character. Such typing may be effected by again actuating the same silent key 39, if desired, to type in another case, since the machine is usually adapted to write either in lower case, in capital case, or in figure case. Types for doing this are shown at 46, 47, and 48, respectively, and are adapted to be brought into use at the actuation of the usual shift keys, not shown herein, said keys adapted to shift the carriage 18, and with it its platen 9.

65 It will be observed that no complicated mechanism need be provided to release the hook 43 from the lug 45, since the next actuation of a letter-feeding key 1 lifts the auxiliary cross-bar 42 by its lug 13, carries the hook 43 clear of the lug 45, and allows the carriage 18 to be drawn along by the spring barrel 19 at the return of the type-key. In order that the hook 43 may have as little lost motion as needed to enable it to be 115 caught upon the lug 45, it may normally rest upon the lug 45 by a cam face 49, and may be provided with a long projecting nose 50, which is adapted to easily and surely catch over the lug 45.

70 In order to enable the space-bar 51 to release the carriage, no special connections need be provided, since it may be mounted upon the usual arms 52 pivoted on one of the usual fixed shafts 3 and provided with the usual rear tail 53 on an arm or lever 52, said tail in rising adapted to strike and actuate both the cross-bar 10 and the auxiliary cross-bar 42, with the result that the carriage is fed.

Variations may be resorted to within the scope of the invention, and portions of the improvements may be used without others.

Having thus described my invention, I

5 claim:

1. In a typewriting machine, the combination with a traveling carriage, of letter-feeding type-keys, silent keys, an escapement-actuating device universal to said letter-feeding keys and said silent keys, a device tending to lock said escapement-actuating device in actuated position when moved thereto, and means, universal to said letter-feeding keys but not to said silent 10 keys, for preventing the locking action of the locking device when the escapement-actuating device is actuated by the letter-feeding keys.

2. In a typewriting machine, the combination with a traveling carriage and letter-feeding type-keys, of a universal bar operated by said keys, silent keys also operating said universal bar, a device on the universal bar for holding it in its operated position, 20 means on the universal bar adapted to move said device, and lugs on said different keys for operating said universal bar and for selectively controlling said means.

3. In a typewriting machine, the combination with a traveling carriage and letter-feeding type-keys, of a universal bar operated by said keys, silent keys also operating said universal bar, a hook on the universal bar, a lug adapted to be caught by the hook, 30 a secondary bar on the universal bar connected to move the hook, and lugs on said different keys adapted to selectively move the hook.

4. In a typewriting machine, the combination with a traveling carriage and type-keys, of levers for said keys, a ribbon-vibrating mechanism, a universal bar operating said mechanism and comprising a solid cross-bar, a secondary cross-bar pivoted upon the universal bar, lugs upon said key-levers for actuating said solid cross-bar, extensions of certain of said lugs adapted to operate the secondary bar, and a hook connected to the secondary bar adapted to selectively lock or leave free the universal bar dependent upon the lug on the key-lever operated.

5. In a typewriting machine, the combination with a traveling carriage, of letter-feeding type-keys, silent keys, an element universal to all of said keys, a device tending to lock said universal element in operated position, and a controller for the locking device universal to said letter-feeding 55 type-keys, whereby actuation of any one of the latter will prevent locking of the universal element in operated position.

6. In a typewriting machine, the combination with a traveling carriage and letter-feeding type-keys, of a universal bar operated by

said keys, silent keys also operating said universal bar, a device on the universal bar for holding it in its operated position, means on the universal bar adapted to move said device, and lugs on said different keys 70 for selectively making the holding device effective or ineffective.

7. In a typewriting machine, in combination, an escapement device, a ribbon carrier, a universal bar for operating said escapement device and said ribbon carrier, means to lock said universal bar in operated position, comprising a hook and a lug to co-operate therewith, keys each comprising a lug adapted to engage said universal bar to operate the same, and said locking device to prevent engagement between said hook and said first-mentioned lug, and a key comprising a lug adapted to engage the universal bar but not said locking device which will become effective by engagement of the hook and the first-mentioned lug upon movement of the universal bar to actuated position.

8. In a typewriting machine, the combination with a traveling carriage, of a ribbon carrier normally holding its ribbon clear of the printing point, letter-feeding keys adapted at their actuation to bring the carrier to the printing point, a spring for returning the carrier, a silent key also adapted to bring the carrier to the printing point, a hook normally tending to move to holding position and effective at the operation of the silent key to hold the carrier at the printing point, and means whereby any of said letter-feeding keys when actuated will shift said hook to ineffective position.

9. In a typewriting machine, in combination, an escapement device, a universal bar for actuating the same, a locking device to hold said universal bar in operated position, said locking device comprising a hook and a lug which may be brought into effective engagement upon movement of the universal bar to its operated position, keys comprising lugs to operate said universal bar and said locking device, and keys comprising lugs adapted to operate said universal bar without operating said locking device.

10. In a typewriting machine, the combination with a universal bar, of a locking device tending to hold the universal bar in actuated position when moved thereto, keys comprising lugs adapted to engage said bar and said device to actuate the bar and to prevent the locking of said bar in operated position respectively, a key comprising a lug adapted to actuate said bar only, and an escapement device and a ribbon carrier both operated by the universal bar.

11. In a typewriting machine, the combination with a universal bar and a movable part thereon, of keys comprising lugs adapted to engage said bar and said part to oper-

ate the same, a key comprising a lug adapted to actuate the universal bar only, an escapement device and a ribbon carrier both operated by the universal bar, a hook connected to said part, and a lug adapted to be caught by said hook or not, according as the movable part remains at rest or is operated.

12. In a typewriting machine, the combination with a universal bar having a solid part, of a part movable on said solid part, keys having levers adapted to engage both the solid part and the movable part, a key having a lever adapted to engage the movable part only, and a locking device for the universal bar selectively operated according as the movable part is actuated or not at the engagement of a key-lever.

13. In a typewriting machine, the combination with a universal bar having a solid part, of a part movable on said solid part, keys having levers adapted to engage both

the solid part and the movable part, a key having a lever adapted to engage the movable part only, a fixed lug upon the machine, and a locking member adapted to engage said lug or not, according as the movable part is actuated.

14. In a typewriting machine, the combination with a universal bar having a solid part, of a part movable on said solid part, keys having levers adapted to engage both the solid part and the movable part, a key having a lever adapted to engage the movable part only, a space-key adapted to actuate both the solid part and the movable part, and a locking device for the universal bar selectively operated, according as the movable part is actuated or not at the engagement of a key-lever.

WILLIAM H. HULSE.
